(57) **CLAIM**

The ornamental design for a thermotherapy apparatus for sofa, as shown and described.

DESCRIPTION

FIG. 1 is a front, left perspective view of a thermotherapy apparatus for sofa showing the claimed design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front, left perspective view of the thermotherapy apparatus for sofa in an unelevated, pulled-out position; and, FIG. 9 is a front, left perspective view of the thermotherapy apparatus for sofa in an unelevated, pushed-in position.

The evenly spaced broken lines illustrate portions of the thermotherapy apparatus for a sofa, forming no part of the claimed design. The dot-dashed broken lines illustrate boundaries to the claim that form no part of the claimed design.

1 Claim, 9 Drawing Sheets
